UNITED STATES PATENT OFFICE.

FERDINAND J. HOHNHORST AND FERDINAND J. KROEGER, OF COVINGTON, KENTUCKY.

MECHANISM FOR TRUING AND DRESSING GRINDING WHEELS.

Application filed May 31, 1924. Serial No. 717,015.

To all whom it may concern:

Be it known that we, FERDINAND J. HOHNHORST and FERDINAND J. KROEGER, citizens of the United States, residing at Covington, 5 in the county of Kenton and State of Kentucky, have jointly invented certain new and useful Improvements in Mechanism for Truing and Dressing Grinding Wheels, of which the following is a specification:

10 Our invention relates to mechanism for truing and dressing grinding wheels, such as emery wheels employed in machinery for grinding or polishing the surfaces of metal in precision grinding, and is employable for 15 truing and dressing the grinding wheel without removing the grinding wheel from the grinding or polishing machine.

It is the object of our invention to provide a plurality of rotary abrading parts 20 having non-parallel axes of rotation arranged to contact the grinding surface of a grinding wheel in such manner that the abrading actions of the respective abrading parts upon the grinding surface of the 25 grinding wheel will be counter to each other; further, to provide a plurality of rotary abrading parts coacting with the grinding surface of the same grinding wheel and presented toward said grinding surface 30 at angles with relation to each other; further, to provide means whereby the angular relation of the abrading parts with relation to each other is adjusted; further, to provide a plurality of rotary abrading wheels 35 supported proximate to each other by bearings at the outsides of said collective abrading wheels; further, to provide means whereby to relatively position said bearings with relation to each other for attachment and 40 removal of the abrading wheels; further, to provide rotary abrading wheels which are tilted toward each other in a plane located within an angle of ninety degrees from that plane parallel to the axis of rotation of the 45 grinding wheel in which said axis and the points of contact of said rotary abrading wheels and said grinding wheel are located; further, to provide means for collectively adjusting said rotary abrading parts in angular relation with the axis of rotation of the 50 grinding wheel; and, further, to provide rotary abrading parts in such respective relations which are normally quiescent, with the rotary motion imparted to the rotary 55 abrading parts by contact thereof with the rotating grinding wheel.

The invention will be further readily understood from the following description and claims, and from the drawings, in which latter:

Fig. 1 is a plan view of our improved device applied to an exemplified grinding machine, partly broken away.

Fig. 2 is a cross-section of the same, taken on the line 2—2 of Fig. 1, and partly broken away.

Fig. 3 is a diagrammatic representation of the relation of the abrading wheels and a grinding wheel viewed from the top.

Fig. 4 is a side elevation of an exemplification of our improved device, partly broken away.

Fig. 5 is a plan view of the same, partly in section on the line 5—5 of Fig. 4.

Fig. 6 is a cross-section of the same, taken on the line 6—6 of Fig. 5.

Fig. 7 is a plan view of our improved device, in which the rotary abrading parts are shown as dressing disks; and,

Fig. 8 is a side elevation of the same, partly broken away.

We have exemplified our invention as employed in connection with a so-called grinding or polishing machine employing a rotary grinding wheel 11 for effecting grinding or polishing.

The work to be ground or polished, which may for instance be a shaft, is arranged to be placed between suitable centers 12, 13, of which 12 may exemplify a head center, arranged to be rotated by suitable driving means, as a pulley 14, a usual quill 15 in which the head-center is supported in usual manner being journaled in a bearing 16 of a head-stock 17, slideable laterally on guideways 18, 19, of a table 20.

The tail-center 13 is mounted in a suitable sleeve 21, movable axially in a bearing 22, in usual manner, the bearing being on a tail-stock 23 laterally adjustable on the guideways 18, 19, of the table 20.

The table is exemplified as pivotally mounted by a pivot 25 on a saddle 26, which has lateral reciprocating motion imparted thereto by power means, in usual manner, as by a pinion 27, suitably driven, meshing with a rack 28 extending lengthwise of the saddle. The saddle is slideable laterally on guideways 29, 30, on the frame 31 of the machine.

The grinding wheel 11 is suitably fixed to a shaft 34 journaled in bearings 35 of a

slide 36, adjustable toward and from the work-table on guideways 37, by any suitable means, the slide being arranged to be clamped by means of suitable T-bolts and nuts 38, the heads of the T-bolts coacting with the T-slot 39 in the frame, and the nuts clamping the slide to the frame. The shaft is rotatable in suitable manner, as by a belt passing about suitable pulleys 40, 41, fixed to the shaft.

In the exemplification, the work located between the centers may be caused to reciprocate axially in planes parallel to the axis of rotation of the shaft of the grinding wheel for grinding or polishing straight work, or the table may be adjusted to an angle with relation to said parallelism, effected, for instance, by rotation of the handle 42 according to the reading on the gage 43.

We have in the present exemplification illustrated a reciprocating table on which to mount the work, the grinding wheel having a stationary position, although the relation of the parts may be reversed, the work being stationarily positioned and the grinding wheel having reciprocations imparted to it. We have instanced the abrading parts as acting on the grinding wheel in the absence of work between the centers. The grinding machine may be of any desirable construction.

The rotary abrading parts are exemplified as abrading wheels 45, 145. These rotary abrading wheels are in their preferred form, illustrated in Figs. 1 to 6 inclusive, of a texture much harder than the grinding wheel and of much smaller diameter than the diameter of the grinding wheel on which they operate. The rotation imparted to the grinding wheel is instanced as in the direction of the arrow *a*, while the rotations imparted to the abrading wheels through the medium of the grinding wheel are instanced as in the directions of the arrows *b*, *c*.

In the modification shown in Figs. 7 and 8 we have illustrated the rotary abrading parts as roughing wheels 45', 145', used primarily for rough-truing or rough-dressing the grinding wheel, and comprising respectively, for example, disks 46 provided with peripheral teeth 47, which may be of hardened metal, other parts of the device shown in Figs. 7 and 8 being exemplified the same as similar parts described particularly with reference to Figs. 1 to 6 inclusive, and designated by similar reference numerals.

The grinding wheel during operation becomes impregnated with particles of dirt or metal from the work being operated on, and becomes comparatively glossy and thereby loses its grinding effect, its granular structure also becoming dull at the

grinding face, thereby reducing its grinding or polishing properties.

By means of our invention, the particles of dirt and metal are removed from the grinding surface of the grinding wheel by 70 coacting rotary abrading parts which act counter to each other or crossingly with relation to each other upon the grinding surface of the grinding wheel, whereby to clear the recesses and pores in the grinding surface, as by having the respective abrading parts coact in different directions for drawing and wiping the particles of dirt and metal out of said recesses and pores, by successive actions thereon by the respective rotary abrading parts, to dislodge the dirt and metal and refuse therefrom, effected, for instance, by the opposite positions and opposite formations of the rotary abrading parts. The rotary abrading parts 75 further coact in different directions with the grinding surface for sharpening the particles or grains in said surface.

The grinding or polishing effect of the grinding wheel is determined by the fineness or coarseness of its grinding surface, and we have provided means whereby to regulate such fineness or coarseness in order to dress the grinding wheel according to the work which it is to perform.

For accomplishing this we preferably so mount the rotary abrading parts as to adjust the angular relation between their axes of rotation, causing increase in angular relation between said axes of rotation when 100 a coarser grinding surface is desired and causing said axes of rotation to be more nearly parallel when a finer grinding surface is desired.

The more said axes of rotation are out of parallel with each other, the greater will be the swirling action of the abrading surface upon the grinding surface, in order to clean the peripheral interstices or pores of the grinding wheel by brushing or drawing out the dirt or particles of metal which may be lodged in said interstices or pores, the swirling action of the respective rotary abrading parts upon the grinding surface being in opposite directions so that the swirling action of one of said rotary abrading parts is to draw the dirt or particles of metal out of the interstices or pores in one direction, whereas the other rotary abrading part acts upon said dirt or particles in the other direction, so as to insure that said particles of dirt and metal are dislodged from said interstices or pores, whereby the cleaning and abrading effect is increased and the time consumed in the operation is decreased, 105 and, furthermore, these oppositely swirling movements aid in producing exceptionally sharp conditions of the particles or grains for enhancing the grinding properties of the grinding wheel, and the oppositely acting 110

abrading parts act to produce true cylindrical form in the grinding wheel.

The abrading wheels are preferably tilted with relation to each other so as to present 5 oppositely inclined paths of rotation to the grinding wheel, and oppositely inclined paths of wiping movement upon the grinding surface of the grinding wheel. The exemplified tilting may be said to be the resultant effect of tilting the abrading wheels in both a horizontal plane and in a vertical plane, producing a tilting in an intermediate direction, or about midway between said planes, for instance, as indicated in 10 Fig. 3.

The abrading wheels preferably have their points of closest approach at points in angles of the outer peripheries of said wheels located between the plane in which 20 the axis of rotation of the grinding wheel and the points of contact between the abrading wheels and said grinding wheel are located and a plane at right angles thereto intersecting the middle portions of the 25 abrading wheels, which angle is an angle within ninety degrees, the points of closest approach being preferably approximately in the middle of said angle for most efficient truing, cleaning and dressing results.

We also prefer to mount the rotary abrading parts so that they may be adjusted about an axis located in or between said rotary abrading parts and in said grinding wheel, so as to present said rotary abrading 30 parts at an additional angle to the rotary grinding wheel. We have instanced this accomplished by mounting the rotary abrading parts collectively on a shank, and adjusting the shank rotatively, for adjusting 35 the positions of the rotary abrading parts with relation to the grinding wheel, means being also provided to adjust the shank axially toward and from the grinding wheel.

The nearer the collective abrading wheels are adjusted into parallelism with the grinding wheel, the finer will be the finish imparted to the grinding wheel, for producing a polishing effect upon the work, and the 50 greater the angle to which the abrading wheels are adjusted with relation to the grinding wheel, preferably not exceeding 30 degrees, the coarser will be the finish imparted to the grinding wheel for cutting effects upon the work.

We shall describe the mounting of the abrading wheel 45, the mounting of the abrading wheel 145 being similar thereto, but having the parts disposed in opposite 60 directions, the parts being designated by similar reference numerals, but increased to the series 100.

Thus the abrading wheel 45 is exemplified as secured to a mandrel 51, provided 65 with a flange 52, and is shown clamped to

said mandrel by means of a nut 53, a washer 54, for instance of leather, being located between the grinding wheel and the flange, and washers 55, 56, the former of leather, being located between the abrading wheel 70 and the nut, the nut clamping said abrading wheel and washers between the flange and the nut, and being threaded over the threaded end 57 of said mandrel.

A bearing-housing 58 has bearings 59, 60, 75 therein for the mandrel, the bearings being shown as combined radial and end-thrust ball-bearings. The ball-bearing 59 comprises an inner race 61 and an outer race 62. The ball-bearing 60 is provided with 80 an inner race 63 and an outer race 64. The inner races are shown secured to the mandrel, the inner race 61 contacting a reduced shoulder 65 on the flange 52 at one end thereof, and being contacted at its other 85 end by a bushing 66 about which the inner race 63 is received against an annular shoulder 67, a nut 68 on the outer threaded end 69 of the mandrel clamping the inner race 61, the bushing 66 and the inner race 90 63 between the shoulder 65 and the nut.

The outer race 62 is received against an annular shoulder 71 in the bearing-housing at one end of said race, a collar 72 separating said outer races 62, 64, and a plug 73, 95 received in the outer threaded socket 74 of the bearing-housing, clamping the outer races and the collar therebetween between the annular shoulder 71 and said plug. This plug forms a closing cap for the outer 100 end of the bearing-housing, there being a compressible washer 75 located between the inner end of the bearing-housing and the rotatable abrading wheel.

The threaded portions of the mandrel are 105 preferably such as to be counter to the direction of rotation of the respective abrading wheels, and they are instanced as right-hand threads on the mandrel 51, and as left-hand threads on the mandrel 151.

The respective bearing-housings 58, 158, 110 are on arms 77, 177, on a shank 78, forming a fork-like support for the rotary abrading parts. The space between the arms is preferably adjustable for adjusting the angle between the rotary abrading parts, and preferably also for convenience of attachment and removal of the rotary abrading parts. We have instanced this adjustment as accomplished by providing the arm 77 115 with wings 80, and providing the arm 177 with wings 180, and providing the shank with a wing 81, a bolt 82 being received through coincident holes in the wings, the parts being clamped together by a nut 83.

The arms respectively have extensions 85, 185, in which bolts 86, 186, are threaded, the inner ends of the bolts having connections with the shank, as by ball and socket joints 87, 187. Nuts 88, 188, are arranged 120 to clamp the bolts in adjusted positions,

The turning of either bolt moves the corresponding arm inwardly or outwardly according to the direction in which the bolt is turned, for adjusting the abrading wheel thereon with relation to the shank.

The abrading wheels are also preferably adjusted about an axis substantially parallel with the axis of the shank, for adjusting the paths of the rotary abrading parts 10 at additional angles to the path of the rotary grinding wheel. This latter adjustment moves one of the abrading wheels upwardly and the other abrading wheel downwardly about the axis of their supporting shank, and presents the abrading wheels to the grinding wheel in such manner as to enhance the swirling effects of the respective abrading wheels in cleaning and removing particles of dust and metal from the 20 interstices and pores in the grinding surface of the grinding wheel, and in sharpening the particles and grains of the grinding wheel.

The means employed for fixing the abrading means to the grinding or polishing machine and permitting said last-named adjustment, are exemplified as follows:

The table of the grinding or polishing machine is, in the present instance, provided 30 with a guide 101 and a rail 102. A clamp 103 is provided with a jaw 104 co-acting with the guide and a clamping means comprising a jaw 106 having an inclined face 107 on the body of the clamp and a clamp-plate 108, the inclined face and the clamp-plate being arranged to clamp upon the rail 102.

A stem 111 is located in a bearing 112 of the clamp. An adjusting nut 115 and a lock nut 116 are received over the threaded end 40 117 of said stem. Said stem is provided with a flattened head 119, a fork 120 of a handle 121 being received about said head and articulated therewith by means of a pin 122.

The head 119 is received through a slot in a cap 126. The inner end of the fork 120 is provided with cams 129 and shoulders 130, arranged to bear against the cap, and to cause clamping movement between said cap and the clamp-plate 108 at one side of the rail 102 and the inclined face 107 at the other side of said rail, causing clamping of the jaw upon said rail.

The body of the clamp is provided with a bearing 135, shown as a clamp-bearing, in which the shank 78 is received, and in which said shank may be adjusted axially and rotatively, for adjusting the relation of the rotary abrading parts to the grinding wheel as hereinbefore explained. When such adjustments have been made, the clamp-bearing is clamped about the shank by means of bolts 136, received through holes of a cheek 138 and threaded in threaded holes of a cheek 140, the cheeks being located

at the respective sides of the split 141 in said clamp-bearing, which is thereby constituted a split-bearing.

The respective arms 77, 177, are provided with flanged guards 44, 144, protectingly received about the rotary abrading wheel.

Our improved device provides ready and convenient means for obtaining quick and effective truing, dressing, cleaning and sharpening of the grinding wheel in novel manner, and provides means which act with a cross-wiping motion in paths which cross each other upon the surface of the grinding wheel for cleaning, truing, dressing and sharpening the grinding surfaces.

Having thus fully described our invention, what we claim as new, and desire to secure by Letters Patent, is:

1. In mechanism for truing and dressing grinding wheels, the combination of a support, a plurality of rotary abrading parts thereon arranged to operate on the same grinding wheel, and means for positioning said rotary abrading parts with their axes of rotation in non-parallel relation.

2. In mechanism for truing and dressing grinding wheels, the combination of a support, a plurality of rotary abrading parts thereon arranged to operate on the same grinding wheel, means for positioning said rotary abrading parts with their axes of rotation in non-parallel relation, and means for adjusting the angle between said axes of rotation.

3. In mechanism for truing and dressing grinding wheels, the combination of a support, a plurality of rotary abrading parts thereon arranged to operate on the same grinding wheel, means for positioning said rotary abrading parts so as to have non-parallel axes of rotation, and means for collectively adjusting said axes of rotation about a common axis.

4. In mechanism for truing and dressing grinding wheels, the combination of a support, a plurality of rotary abrading parts thereon arranged to operate on the same grinding wheel and having axes of rotation, and means for positioning said rotary abrading parts on a plurality of axes respectively substantially perpendicular to said axes of rotation and substantially perpendicular to each other.

5. In mechanism for truing and dressing grinding wheels, the combination with a grinding wheel, of a plurality of rotary abrading wheels arranged to contact therewith relatively angularly positioned and having their closest approach at points in the outer peripheries of said abrading wheels between their points of contact with said grinding wheel and an angle of ninety degrees thereto in said abrading wheels.

6. In mechanism for truing and dressing grinding wheels, the combination with a

grinding wheel, of a plurality of rotary abrading wheels in planes which are non-parallel to each other, said abrading wheels having their closest approach at a point in 5 the angle between that plane of the axis of rotation of the grinding wheel in which the axes of rotation of the abrading wheels are located and a plane at right angles thereto intersecting said last-named axes of 10 rotation.

7. In mechanism for truing and dressing grinding wheels, the combination with a grinding wheel, of a plurality of normally quiescent rotary abrading wheels arranged 15 to contact said grinding wheel and located in planes tilted toward each other in the angle between that plane parallel to the axis of rotation of the grinding wheel in which said axis and the points of contact between 20 said wheels are located and a plane at right angles thereto in which the axes of rotation of the abrading wheels are located, and arranged whereby said rotary abrading wheels rotate in angular relation on contact with 25 said rotating grinding wheel.

8. In mechanism for truing and dressing grinding wheels, the combination of a plurality of normally quiescent rotary abrading parts arranged to operate on the same grinding 30 wheel, and means for positioning said rotary abrading parts on non-parallel axes of rotation, and arranged whereby said rotary abrading parts rotate in angular relation on contact with a rotating grinding 35 wheel.

9. In mechanism for truing and dressing grinding wheels, the combination of a plurality of normally quiescent rotary abrading parts arranged to operate on the same 40 grinding wheel, and means for positioning said rotary abrading parts at angles with relation to each other and to said grinding wheel, whereby on contact between said rotary abrading parts and said grinding wheel 45 said rotary abrading parts are caused to rotate, with a differential wiping action in opposite directions on said grinding wheel.

10. In mechanism for truing and dressing grinding wheels, the combination with a 50 grinding wheel, of a support, a plurality of rotary abrading wheels thereon arranged to operate on the said grinding wheel, and means for positioning said rotary abrading wheels on said support with their axes of rotation 55 arranged at an angle with relation to each other and to said grinding wheel.

11. In mechanism for truing and dressing grinding wheels, the combination with a 60 grinding wheel, of a plurality of rotary abrading wheels arranged to operate on said grinding wheel, and means for positioning said rotary abrading wheels on said support with their axes of rotation arranged at an angle with relation to each other and with 65 their axes of rotation combinedly at a dif-

ferent angle to the axis of rotation of the grinding wheel.

12. In mechanism for truing and dressing grinding wheels, the combination with a grinding wheel, of a plurality of rotary 70 abrading wheels arranged to operate on said grinding wheel, and means for positioning said rotary abrading wheels with their axes of rotation arranged at an angle with relation to each other in a given plane and at 75 angles with relation to the axis of rotation of said grinding wheel in a different plane.

13. In mechanism for truing and dressing grinding wheels, the combination with a grinding wheel, of a plurality of rotary 80 abrading wheels, means for positioning said rotary abrading wheels with their axes of rotation arranged at an angle with relation to each other in a given plane, and means for adjusting the distance and angle between 85 the proximate abrading portions of said rotary abrading wheels.

14. In mechanism for truing and dressing grinding wheels, the combination of rotary 90 mandrels in endwise relation to each other, abrading wheels on proximate ends of said mandrels, and bearings for said mandrels at the outside faces of said abrading wheels, said bearings positioned at an angle with 95 relation to each other.

15. In mechanism for truing and dressing grinding wheels, the combination of rotary mandrels in endwise relation to each other, abrading wheels on the proximate ends of 100 said mandrels, bearings for said abrading wheels at the outside faces of said abrading wheels, said bearings positioned at an angle with relation to each other, and a shank on which said bearings are mounted.

16. In mechanism for truing and dressing grinding wheels, the combination of rotary 105 mandrels in endwise relation to each other, abrading wheels on the proximate ends of said mandrels, bearings for said mandrels at the outside faces of said abrading wheels, said bearings positioned at an angle with 110 relation to each other, a shank on which said bearings are mounted, and means for positioning said bearings about an axis substantially parallel with said shank.

17. In mechanism for truing and dressing grinding wheels, the combination of rotary 115 mandrels in endwise relation to each other, abrading wheels on the proximate ends of said mandrels, bearings for said mandrels at the outside faces of said abrading wheels, said bearings positioned at an angle with 120 relation to each other, a shank on which said bearings are mounted, a bearing for said shank, and means for axially and rotatively adjusting said shank in said last-named bearing.

18. In mechanism for truing and dressing 125 grinding wheels, the combination of a pair of arms, a bearing on each of said arms, a

mandrel in each of said bearings, and means for adjusting the angle between said arms whereby to adjust the angular relation between said mandrels, the proximate ends of 5 said mandrels between said bearings arranged for receiving abrading wheels.

19. In mechanism for truing and dressing grinding wheels, the combination of a pair of arms, a bearing on each of said arms, a 10 mandrel in each of said bearings, means for changing the distance relations between said bearings, the proximate ends of said mandrels between said bearings arranged for receiving abrading wheels, and means 15 for fixing the approach relation between said arms, whereby separation between said arms permits insertion and removal of abrading wheels on the proximate ends of said mandrels.

20. In mechanism for truing and dressing grinding wheels, the combination of a support, arms pivoted thereon provided with ends swinging with relation to said support, a bearing on each of said swinging ends, a 25 mandrel in each of said bearings, the proximate ends of said mandrels between said bearings arranged for receiving abrading wheels, means for adjusting the distance relations between said swinging ends, and 30 means for securing said arms in adjusted relations.

21. In mechanism for truing and dressing grinding wheels, the combination of a sup-

port, a pair of arms provided with wings, 35 means for pivoting said wings to said support, a bearing at one end of each of said arms, a mandrel in each of said bearings, the proximate ends of said mandrels arranged for receiving abrading wheels, and 40 adjusting means between the other ends of said arms and said support whereby to adjust the angular relation between said bearings.

22. In mechanism for truing and dressing grinding wheels, the combination of a support, a pair of arms, said support and said 45 respective arms provided with complementary wings pivoted together for swinging relation of said arms on said support, a bearing in the swinging end of each of said arms, a mandrel in each of said bearings, the proximate ends of said mandrels between 50 said bearings arranged for receiving abrading wheels, means for adjusting said arms on said support, and a clamp for clamping together said wings for fixed relation of said arms on said support.

In testimony whereof, we have hereunto signed our names in the presence of two subscribing witnesses.
